UNITED STATES PATENT OFFICE.

AUGUST WILL, OF JERSEY CITY, NEW JERSEY, ASSIGNOR TO DAVID WOLFE BRUCE, OF NEW YORK, N. Y.

DESIGN FOR A FONT OF PRINTING-TYPES.

SPECIFICATION forming part of Design No. 12,004, dated October 26, 1880.

Application filed August 20, 1880. Term of patent 14 years.

To all whom it may concern:

Be it known that I, AUGUST WILL, (assignor to DAVID WOLFE BRUCE,) of Jersey City, Hudson county, New Jersey, have invented and produced a new and original Design for a Font of Printing-Types, of which the following is a specification.

The nature of my design is clearly shown in the accompanying typographic impression, to which reference is made; and it consists of a letter of the mediaeval period, the up-and-down portions of which are bounded by the heavy lines having inclined sides, as shown. These lines having inclined sides occur at the top and bottom of all the letters save in the C, E, F, G, H, S, T, and Z.

In the C, E, G, and S the right-hand portion of the upper cross-line is continued downward and forms a triangular termination, from which projects about centrally a vertical line. In the letter F, from the upper cross-line upon the right hand proceeds the curved line, extending below the central part of the letter and terminating in the ball termination. In the letter H the upper cross-line upon the right has the triangular termination. In the letters T and Z the upper cross-line upon the left has the triangular termination, followed, in the case of the Z, by a short vertical line projecting downward.

All the letters are ornamented by the heavy dots, as shown in the A and F. These dots are placed above and below the cross-lines of the letters—in the M, W, X, and Z upon each side of the central portion of the letters.

The symbol & has its base bounded by a heavy line having the inclined side upon the left, and the motive of the design is preserved in the hyphen, composed of the cross-line connected at each end to the lines with inclined sides, and in the exclamation and interroga-³⁵tion points bounded upon their upper sides by the cross-lines with inclined sides.

In the figures 3, 4, 6, 8, 9, and 0 these bounding-lines are found both above and below, in the figures 1, 5, and 7 at the base of the figures, and in the figure 2 above the figure. The heavy dots are found in the figures 2, 4, 5, 6, 7, 8, 9, and 0, and in the dollar and pound symbols the cross-lines, with inclined sides, occur at the base of the dollar and at the top and bottom of the pound.

Having now set forth my invention, what I claim as new is—

The design for a font of printing-type, substantially as shown and described.

AUGUST WILL.

In presence of—

WILLIAM V. H. HICKS,
A. SIDNEY DOANE.
